CLAIM

I claim the ornamental design for a twisted pendant, as shown and described.

DESCRIPTION

FIG. 1 is a first side perspective view of a twisted pendant according to the design having a substantially rectangular shape and being twisted with respect to its longitudinal axis; FIG. 2 is a second side perspective view from the opposite side thereof;

FIG. 3 is a plan view thereof, the opposite plan view being equal;

FIG. 4 is a side view thereof, the opposite side view being equal;

FIG. 5 is a top side view thereof; and,

FIG. 6 is a bottom side view thereof.
